[57] **ABSTRACT**

An improved aqueous drilling fluid having low fluid

loss and effective viscosity control is obtained by the addition of a cold-water-swelling granular corn starch material which consists essentially of substantially intact, partially swollen granules which appear nonbirefringent under a polarizing microscope and which have a cold-water solubility of at least 50%. The improved drilling fluids exhibit better controlled fluid loss and viscosity stability at temperatures up to 250° F. than do drilling fluids containing most present commercially available starch-based fluid loss control agents.
